UNITED STATES PATENT OFFICE.

THOMAS A. FOX, OF NEWARK, NEW JERSEY, ASSIGNOR TO THE STEFFENS-AMBERG CO., OF NEWARK, NEW JERSEY, A CORPORATION OF NEW JERSEY.

DESIGN FOR A TURNBACK LOOP FOR HARNESS.

46,398.

Specification for Design.

Patented Sept. 15, 1914.

Application filed August 9, 1913. Serial No. 783,945. Term of patent 7 years.

To all whom it may concern:

Be it known that I, THOMAS A. FOX, a citizen of the United States, residing at Newark, county of Essex, and State of New Jersey, have invented a new, original, and ornamental Design for Turnback Loops for Harness, of which the following is a specification, reference being had to the accompanying drawing, forming part thereof.

Figure 1 is a top view of a turn-back loop

for harness showing my new design. Fig. 2 is a side view, and Fig. 3 is an end view.

I claim:

The ornamental design for a turn-back loop for harness, as shown.

THOMAS A. FOX.
